UNITED STATES PATENT OFFICE.

ARTHUR J. JACKMAN, OF FOREST HILLS BOROUGH, PENNSYLVANIA, ASSIGNOR TO THE
VESUVIUS CRUCIBLE COMPANY, OF SWISSVALE, PENNSYLVANIA, A CORPORATION
OF PENNSYLVANIA.

FURNACE STRUCTURE.

Application filed August 18, 1926. Serial No. 129,953.

This invention relates to furnace structures and more especially to a composite furnace lining having a facing layer of non-spalling veneer brick supported on a backing 5 layer of ordinary furnace brick. While the composite lining may be used for various purposes in furnaces, it is particularly adapted for so-called suspended arch furnace roofs, which are either flat or have but a slight 10 curvature and in which the brick work forming the roof or lining is hung from supporting beams. The roof brick are ordinarily made with recesses in the upper faces for the reception of iron hangers which 15 support the brick from supporting beams. The ordinary refractory brick such as are commonly used for furnace linings and for the flat arches spall off or crack under conditions of use particularly under the temperature variations to which the furnace linings 20 are subjected in use.

A flat suspended furnace roof is structurally different from an arched roof. In an arched roof the brick are under compression so that if they crack they are ordinarily held in place, whereas in a flat roof or flat arch if a brick cracks there is nothing to prevent the cracked off portion from falling down into the furnace. This not only causes 25 the roof to be injured, but the pieces of brick falling into the furnace chamber are liable to damage the wares being heated therein.

While ordinary furnace brick will spall 30 or crack under the temperature variations and has therefore caused considerable trouble in flat arched roofs, certain ceramic materials may be made into non-spalling brick. An example of such material is that described in my Patent Number 1,577,124 of 35 March 16, 1926. Another non-spalling refractory material is suitably bonded silicon carbide blocks. These materials, however, are relatively expensive, and usually have 40 a much higher heat conductivity than the ordinary clay brick used for furnace roofs and walls.

In my furnace structure, there is a backing layer of ordinary relatively poor heat-conducting brick and a facing layer of non-spalling veneer brick. The veneer brick have supporting extensions which extend through the layer of backing brick and serve 45 to support the veneer brick from points at or near the outside of the backing brick

layer. The joints between the veneer brick are preferably staggered with respect to the joints between the backing brick, thus preventing a direct passage for the heated gases through the wall and protecting the sides 60 of the backing brick from infiltration of the hot gases.

In the drawings which illustrate the preferred embodiment of my invention, Fig. 1 is a vertical section through a furnace 65 having a flat arch or supported roof and side walls embodying the invention.

Fig. 2 is a plan view of a portion of the roof.

Figs. 3 and 4 are vertical sections taken 70 along the lines III—III and IV—IV of Fig. 2.

Fig. 5 is a detailed perspective view showing the assembly of the backing and veneer brick. 75

Fig. 6 is a perspective view showing a detached veneer brick.

Fig. 7 is a perspective view showing a modified form of backing and veneer brick.

Referring to the illustrated embodiment 80 of the invention, reference numeral 1 indicates generally a furnace having side walls 2 and a roof 3. The roof is of the flat arch type, in which the roof brick work is hung from supporting beams 4 by means of 85 hangers 5. The roof is formed of a composite lining made up of backing brick 6 and veneer brick 7. The backing brick 6 are preferably of the usual refractory clay brick employed for furnace structures. 90 These brick are poor heat conductors and are relatively inexpensive.

The veneer brick 7 are made of a non-spalling material. The roof is supported by means of the hangers 5 which engage in 95 slots 8 in the backing brick 6, this being the usual way of supporting a flat arched furnace roof. The veneer brick 7 have integral supporting extensions or hanger lugs 9 which extend through square openings between the corners of the backing brick 6. These square openings are formed by the beveled edges 10 of the backing brick. The supporting lugs 9 of the veneer brick have 100 holes 11 in them for the reception of pins 12 which support the veneer brick by contact with the upper faces of the backing brick.

The supporting hangers 9 have a cross section relatively small, compared with the 110

horizontal cross sectional areas of the backing brick so that there is a relatively small heat loss, in case the material of the non-spalling veneer brick is of greater heat conductivity than that of the clay backing brick. As shown in the drawings, the supporting extensions 9 have a cross sectional area approximately 12% to 13% of the area of the furnace lining, thus effectively limiting the area of the material of good thermal conductivity. The cross sectional area of the supporting extensions should be always relatively small compared with the area of the lining; not over a third, and preferably not over a fifth of the area of the lining. The heat loss is therefore effectively limited, preventing excessive waste of heat from the furnace chamber and damage to the superstructure which would result if the entire area of the lining were made of the higher heat-conducting material.

The joints between the veneer brick 7 are staggered with relation to the joints between the backing brick 6 so that the heated gases do not have a direct passage between the veneer brick to the joints between the backing brick. This keeps the infiltration of gases through the lining to a minimum and protects the backing brick against cracking. Moreover, if the corners or lower faces of the backing brick should crack, they would be supported by the veneer brick.

The side walls 2 of the furnace are preferably of a similar structure comprising the backing brick 6 and veneer brick 7 formed in the same way, except that supporting pins need not be put through the tying in lugs or extensions on the veneer brick.

In Fig. 7 is shown a modification in which the backing brick 6^a have the usual hanger receiving slots 8^a. The corners of the backing brick are not beveled off but the veneer brick 7^a are supported by integral extensions 9^a which extend between courses of the backer brick being provided with L-shaped extensions 13 which fit over shoulders 14 on the backer brick. The veneer and backer brick are preferably arranged so as to have their joints staggered.

While I have specifically illustrated and described the preferred embodiment of my invention, it is to be understood that the invention is not limited to its illustrated embodiment but may be otherwise embodied within the scope of the following claims.

I claim—

1. A furnace having a suspended arch roof comprising a layer of backing brick having hanger-receiving slots in their upper surfaces, hangers engaging said slots for supporting the backing brick, and a facing layer of non-spalling veneer brick having supporting extensions extending into the layer of backing brick and provided with supporting means engaging the backing brick

at points above the points of support of the backing brick by their hangers, whereby the material of the backing brick between the points of support of the veneer brick from the backing brick and the backing brick from their hangers is under compression.

2. A furnace having a suspended arch roof comprising a layer of backing brick having hanger-receiving slots in their upper surfaces and having openings through the backing brick structure, hangers engaging the slots for supporting the backing brick, and a facing layer of non-spalling veneer brick having supporting extensions extending through said openings to the upper side of the backing brick and provided with means for supporting the veneer brick therefrom, the joints between the veneer brick and the backing brick being staggered.

3. A composite furnace lining comprising a layer of backing brick of relatively low thermal conductivity having openings through said layer, a facing layer of non-spalling veneer brick of relatively high thermal conductivity, the veneer bricks having supporting extensions received in the openings in the layer of backing brick and extending to points adjacent the outside thereof and serving to support the veneer brick.

4. A composite furnace lining comprising a layer of backing brick having openings through said layer, a facing layer of veneer brick of a refractory material more resistant to spalling than that of the backing brick, the veneer bricks having integral supporting extensions received in the openings in the layer of backing brick and extending to points adjacent the outside thereof, and means engaging the supporting extensions adjacent the outside of the backing brick layer for supporting the veneer brick.

5. A composite furnace lining comprising a layer of backing brick having openings through said layer and a facing layer of veneer brick of a refractory material more resistant to spalling than that of the backing brick, the veneer bricks having supporting extensions received in the openings in the layer of backing brick and extending to points adjacent the outside thereof and serving to tie the veneer brick to the backing brick.

6. A composite furnace lining comprising a layer of backing brick arranged with openings through said layer and a facing layer of veneer brick of a refractory material more resistant to spalling than that of the backing brick, the veneer bricks having supporting extensions extending through the openings in the layer of backing brick and serving to support the veneer bricks from points adjacent the outside of the layer of backing brick.

7. A composite furnace lining comprising a layer of backing brick arranged with openings through said layer and a facing layer of veneer brick of a refractory material more resistant to spalling than that of the backing brick, the veneer bricks having supporting extensions extending through the openings in the layer of backing brick to points adjacent the outside thereof, the joints between the veneer brick and backing brick being staggered. 70
8. A composite furnace lining comprising a layer of backing brick of relatively low thermal conductivity arranged with openings through said layer, and a facing layer of non-spalling veneer brick of relatively high thermal conductivity having supporting extensions received in the openings in the layer of backing brick and extending to points adjacent the outside thereof and serving to support the veneer brick, the cross sectional area of the supporting extensions being not over one-third the area of the lining. 75
9. A composite furnace lining comprising a layer of backing brick of relatively low thermal conductivity arranged with openings through said layer, and a facing layer of non-spalling veneer brick of relatively high thermal conductivity having supporting extensions received in the openings in the layer of backing brick and extending to points adjacent the outside thereof and serving to support the veneer brick, the cross sectional area of the supporting extensions being not over one-fifth the area of the lining. 80
10. A composite furnace lining comprising a layer of octagonal backing brick contiguous to one another on four sides, and a layer of non-spalling veneer brick having integral supporting extensions extending through the openings in the layer of backing brick formed at the corners of the backing brick. 85
11. A composite furnace lining comprising a layer of backing brick having openings through said layer, and a facing layer of non-spalling veneer brick having supporting extensions extending through said openings to points adjacent the outside of the layer of backing brick, the backing brick except at the edges of the lining being contiguous to other backing brick on four sides and contiguous to the supporting extensions of the veneer brick on four sides, the veneer brick on the furnace face of the lining except at the edges of the lining being contiguous on all sides to other veneer brick. 90
12. A furnace having a suspended arch roof comprising a layer of backing brick having openings through said layer, and a facing layer of veneer brick of a refractory material more resistant to spalling than that of the backing brick, the veneer bricks having supporting extensions received in said openings and extending to points adjacent the upper side of the backing brick layer and provided with means for supporting the veneer brick. 95
13. A furnace having a suspended arch roof comprising a layer of backing brick of relatively low thermal conductivity, and a facing layer of non-spalling veneer brick of relatively high thermal conductivity, the veneer bricks having supporting extensions extending between the brick of the backing layer to points adjacent the upper side of the layer of backing brick, said extensions being provided with means for supporting the veneer brick. 100
14. A furnace having a suspended arch roof comprising a layer of backing brick and a facing layer of non-spalling silicon carbide veneer brick, the veneer bricks having supporting extensions extending between the backing bricks to points adjacent the upper side of the layer of backing brick and provided with means for supporting the veneer brick, the backing brick being of a material of low thermal conductivity relative to silicon carbide. 105
15. A furnace having a suspended arch roof comprising a layer of backing brick having openings through said layer, and a facing layer of non-spalling veneer brick having supporting extensions received in said openings and extending to points adjacent the upper side of the backing brick layer and provided with means for supporting the veneer brick, and hangers for supporting the backing brick. 110
16. A furnace having a suspended arch roof comprising an upper layer of backing brick and a lower or facing layer of veneer brick of a refractory material more resistant to spalling than that of the backing brick, the veneer brick layer having supporting extensions extending through the layer of backing brick to points above the upper side of such layer, and supporting means engaging the upper ends of said extensions whereby the veneer brick layer is supported from points at the upper side of the backing brick layer. 115
17. A furnace having a suspended arch roof comprising an upper layer of backing brick and a lower or facing layer of veneer brick of a refractory material more resistant to spalling than that of the backing brick, the veneer brick layer having supporting extensions extending within the layer of backing brick to points adjacent the upper side of such layer, and supporting means engaging said extensions at points adjacent the upper side of the backing brick layer. 120
- In testimony whereof I have hereunto set my hand.
